UNITED STATES PATENT OFFICE.

SYLVAIN EICHHART, OF ST. FONS, NEAR LYONS, FRANCE, ASSIGNOR TO SOCIÉTÉ CHIMIQUE DES USINES DU RHÔNE, ANCIENNEMENT GILLIARD, P. MONNET ET CARTIER, OF LYONS, FRANCE, A CORPORATION OF FRANCE.

PRINTING COMPOUND OF ORTHONITROPHENYL LACTOKETONE.

SPECIFICATION forming part of Letters Patent No. 772,560, dated October 18, 1904.

Application filed June 16, 1902. Serial No. 111,931. (No specimens.)

To all whom it may concern:

Be it known that I, SYLVAIN EICHHART, chemist, of the works of Société Chimique des Usines du Rhône, anciennement Gilliard, 5 P. Monnet et Cartier, St. Fons, near Lyons, France, have invented certain new and useful Improved Preparations of O-Nitro-Phenyl-Lacto-Ketone Suitable for Dyeing and Printing, of which the following is a specification.

10 This invention relates to novel preparations or compositions of o-nitro-phenyl-lacto-ketone suitable for dyeing and printing. These preparations can be readily transformed into indigo by the action of alkalies.

15 It has already been proposed to employ o-nitro-phenyl-lacto-ketone in the printing of textile materials with indigo colors; but up to the present, owing to the insolubility of the product, it has not been possible to employ 20 this ketone in a direct manner. Technical results have only hitherto been obtained with this ketone by using its bisulfite compound, which is soluble in water. The bisulfite compound is, however, unstable, and the actual 25 yield of indigo obtained by its development on the fiber is very much below the theoretical quantity, so that it is no longer in commerce.

I have now discovered that soluble organic 30 sulfonic and carboxylic acids and the soluble salts or organic sulfonic and carboxylic acids render nitro-phenyl-lacto-ketone easily soluble in water and that the mixture of these products with the ketone require simply to be 35 dissolved in water to be ready for use. For the purposes of this invention the acids mentioned are the equivalents of the salts, being, in effect, salts of hydrogen. Of the fatty-acid series there may be employed, for instance, acetic acid, lactic acid, sulfonated 40 oleic acid, their soluble mineral salts and esters, Turkey-red oil, (the ammonia salt of ricinoleic acid, sulfonic acid, and similar bodies. Of the aromatic series the sulfonic acids of 45 benzene, toluene, naphthalene, and naphthol and their soluble salts, as well as the salts of

benzoic acid, salicylic acid, and the like, have been found suitable.

Example I: One kilo o-nitro-phenyl-lacto-methyl-ketone and three kilos p-toluene-sulfonate of sodium are mixed. The product keeps well, it is easily soluble in six liters water, and can be employed for printing textiles or otherwise.

In the printing of textile materials the following example illustrates the practical application of my invention; but it will be understood that it is not confined to the example, the details of which may be varied.

Example II: Ten grams o-nitro-phenyl-lacto-methyl-ketone, one hundred cubic centimeters acetic acid of forty per cent. strength, forty cubic centimeters water, one hundred and fifty grams thickening. After printing the material with the mixture it is dried and 65 then passed through a solution of caustic soda of, say, fifteen per cent. strength to develop the indigo on the fiber.

Example III: Mix twenty grams o-nitro-phenyl-lacto-methyl-ketone with fifty grams Turkey-red oil. Heat the mixture to 50° centigrade. When completely dissolved, add nine hundred and thirty grams of thickening. The color is then ready for printing.

It will be understood that the above examples are merely typical of the invention, which is in no way limited to the particular solubilizing agent specified nor to the proportions mentioned.

What I claim, and desire to secure by Letters Patent, is—

1. A composition of matter soluble in water and suitable for dyeing and printing, including a mixture of o-nitro-phenyl-lacto-ketone and Turkey-red oil (ammonia salt of ricinoleic acid, sulfonic acid.)

2. A composition of matter soluble in water and suitable for dyeing and printing, including a mixture of o-nitro-phenyl-lacto-ketone and a soluble sulfonated carboxylic compound.

3. A composition of matter soluble in water

and suitable for dyeing and printing, including a mixture of o-nitro-phenyl-lacto-ketone and a soluble sulfonic compound.

4. A composition of matter soluble in water and suitable for printing, including a mixture of o-nitro-phenyl-lacto-ketone, a soluble sulfonic compound, and a thickening agent.

5. A composition of matter soluble in water and suitable for dyeing and printing, includ-

ing a mixture of o-nitro-phenyl-lacto-ketone and a soluble sulfonic salt.

In witness whereof I have hereunto signed my name in the presence of two subscribing witnesses.

SYLVAIN EICHHART.
